ATION OF OHIO.

HEAD-CLAMPING DEVICE.

Application filed February 21, 1924. Serial No. 694,390.

Our invention relates to head clamping devices adapted for use in connection with radial drills.

Heretofore it has been customary to position the operative handle of head clamping devices adjacent the top portion of the radial drill arm whereby considerable inconvenience is experienced in operating the device. The top portion of the arm of a radial drill is usually inconveniently accessible to the operator of the radial drill and sometimes it is necessary for the operator to stand upon an elevated support for the purpose of grasping the manually operated handle of the head clamping device. Considerable time is, therefore, consumed and wasted by the operator, caused by the usual inconvenient location of the head clamping operative handle. Furthermore, the operator of the radial drill is endangered when reaching upwardly and over moving parts of the mechanism for the purpose of grasping and operating the handle of the head clamping device.

The objects of our invention are to provide mechanism whereby the operating lever of a head clamping device is conveniently positioned for manual operation by the operator of the radial drill; to provide a head clamping device having an operating lever positioned adjacent the lower edge of the radial drill arm and in close proximity to the radial drill spindle whereby both the head clamping operating lever and the spindle may each be operated without undue loss of time by the operator when desiring to operate both devices in sequence.

Our invention consists in providing a manually operated lever fixed to a vertical rod journaled in supports integral with the radial drill arm and having the upper end of said rod fixed to a horizontal rockable lever having a horizontal plate pivotally connected thereto and actuating means for a plurality of tightening screws comprising a plurality of crank arms pivotally connected to said plate and each of said crank arms having a tightening screw fixed in one end thereof and said screws threaded and projecting through a portion of said head adjacent said arm and adapted to force a gib in close contact with the upper edge of the top rail of said arm when said lever is actuated.

Our invention also consists in the construc-

tion, combination and arrangement of parts as herein set forth and claimed.

55

In the drawing:

Fig. 1 is a front elevation of a radial drill showing the head partly broken away and having our invention attached thereto;

Fig. 2 is a perspective view of our invention shown in enlarged form and having parts of the connecting rod broken away;

Fig. 3 is a section taken on a line corresponding to 3—3 of Fig. 1; and

Fig. 4 is a side elevation of our tightening screw.

A usual radial drilling machine may comprise a base 1 from which column support 2 extends upwardly having vertical column 3 rotatably mounted thereon and arranged to be clamped in adjusted positions by means of eccentric clamp 4 actuated by manually operated lever 5. A horizontal drill arm 6 extends from the column and is slidably mounted thereon as by end 7 forming a bearing around the column. Eccentric clamps 8, respectively, actuated by manually operated levers 9 provide clamping means for securing arm 6 in vertically adjusted positions on the column.

80

The arm 6 has integral upper and lower rails 10 and 11, respectively, extending longitudinally thereof. The upper rail 10 slidably supports drill head 12 having suitably secured therein vertical spindle 13 for receiving tool 14 in the lower end thereof.

85

The head 12 is provided with longitudinal support 15 having integral flange 16 extending downwardly and engaging the outer edge of upper rail 10 whereby the top portion of the head is maintained against outward movement relative to arm 6. A gib 17 is disposed intermediate support 15 and upper rail 10 engaging the top surface thereof and adapted to travel with head 12. The bottom of lower rail 11 is provided with a downwardly extending angular surface 18 adapted to engage upwardly extending angular surface 19 of integral longitudinal support 20 of head 12, whereby the lower portion of the head is maintained against outward movement relative to arm 6.

90

Manually operated means for sliding head 12 over rail 10 longitudinally of arm 6, thereby imparting lateral movement to the head relative to column 3, comprises manually op-

95

105

erated hand wheel 21 fixed to shaft 22 rotatable in bearing 22' and 22" in head 12, and having pinion 23 fixed thereto and meshed with rack 24 fixed to the bottom of upper rail 10 and extending longitudinally thereof.

For use in combination with the afore-described usual mechanism which may comprise a radial drill we provide means for clamping head 12 against longitudinal movement relative to arm 6. Our preferred mechanism comprises vertical rod 25 extending transversely of arm 6 and rotatably secured in bosses 26 and 27 integral with head 12 and positioned at its front inner corner thereof.

15 A manually operated hand lever 28 positioned near the lower edge of arm 6 and in close proximity to spindle 13 is fixed to the lower end of rod 25 and in engagement with the bottom of boss 27 by pin 29. A rockable arm 20 30 is fixed by pin 31 to the upper end of rod 25 and in engagement with the top of boss 26 adjacent the upper edge of arm 6. The rockable arm has slot 32 in its outer end for receiving the inner end 33 of horizontal bar 34 25 pivotally connected to the rockable arm by pin 35. The horizontal bar 34 extends outwardly from column 3 and in parallel relation to arm 6 and has slotted end 36 of spaced apart tightener crank arms 37 pivotally connected thereto by pins 38. Each of the other ends 37' of tightener crank arms 37 has vertical hexagon hole 39 formed therein for receiving hexagon end 40 integral with tightener screw 41 having right hand thread 42 35 cut on its lower portion, and circumferential shoulder 43 adjacent the upper part of the thread. Shoulder 43 is adapted to engage the lower side of tightener crank arm 37 thereby maintaining top 44 of screw 41 substantially flush with the top of tightener crank arm 37. The tightener screws 41 are vertically threaded to support 15 which is less in thickness than the length of threaded portion 42 of the screws thereby permitting the 45 lower ends of the screws to project through the support in engagement with gib 17 whereby right hand direction of rotation of the screws cause the gib to closely engage the top surface of upper rail 10 thereby causing angular surface 19 of support 20 to engage angular surface 18 of lower rail 11 for the purpose of locking head 12 against lateral movement on arm 6.

The operation of the mechanism of our invention in combination with the mechanism which comprise a usual radial drilling machine is as follows:

Manually operated lever 28 positioned in close proximity to spindle 13 and near the 60 lower edge of arm 6 is pulled outwardly whereby vertical rod 25 rotatably mounted in bosses 26 and 27 and having its lower end fixed to lever 28 by pin 29 and having its upper end fixed to rockable arm 30 by pin 31 65 causes slotted outer end 32 of rockable arm

30 to move outwardly relative to column 3. Outward lateral movement is thereby imparted to horizontal bar 34 having end 33 pivotally connected to rockable arm 30 in slot 32; the horizontal bar in turn imparts outward motion to ends 37' of spaced apart tightener crank arms 37 having slots 36 for receiving horizontal bar 34 and pivotally connected thereto by pins 38. Each end 37' of the tightener crank arm, having hexagon hole 39 therein and receiving hexagon end 40 of tightener screws 41 is thereby rotated causing threaded portion 42, screwed in support 15 integral with head 12, to move downwardly to contact with gib 17, thereby forcing the gib in close contact with the upper surface of upper rail 10 and causing angular surface 19 of support 20 of head 12 to closely engage angular surface 18 of lower rail 11, whereby head 12 is locked against lateral movement on arm 6.

The combination mechanism of the radial drill for axially and laterally positioning drill 14 fixed in spindle 13 comprises usual lever 5 rotatably mounted in column support 2 and provided with eccentric means 4 whereby drilling arm 6 is permitted to revolve around column 3. The usual manually operated hand wheel 21 is then rotated in a direction corresponding to the desired lateral movement of drill 14 whereby the combination mechanism which permits arm 6 to revolve around column 3 and which permits lateral movement of head 12 on arm 6 enables the operator of the radial drill to position the drill laterally with relation to any portion of the work being done. The usual lever 5 is then actuated for securing arm 6 against revolving movement around column 3 and manually operated lever 28 is pulled outwardly causing gib 17 to closely engage the upper surface of rail 10 thereby forcing angular surface 19 downwardly and in locking engagement with angular surface 18 whereby head 12 is locked against lateral movement on arm 6. The drill 14 is now securely locked in position in spindle nose 13 for drilling a vertical hole at a desired axial location in the work usually supported by base 1. For axial adjustment of drill 14 levers 9 or other usual mechanism (not shown) are then actuated whereby eccentric clamps 8 or other mechanism permits vertical movement of spindle nose 13 thereby permitting drill 14 to be lowered near engagement with the object positioned on base 1.

The drill 14 is now further positioned laterally and axially for fine adjustments with reference to the work and the usual mechanism for rotating the drill may be actuated.

We have, therefore, provided an extremely simple, efficient, economical and practical device whereby the head of a radial drill may be securely locked against lateral movement upon the arm of the radial drilling machine

wherein the manually operated lever 28 for locking the head is conveniently positioned adjacent and in close proximity to drill spindle 13 and near the lower edge of arm 6.

- 5 Furthermore, by positioning the operating lever of the head clamping mechanism near the lower edge of arm 6 we have not only provided an extremely convenient operable position for the lever but we have also minimized chances of injury to the radial drill 70 operator caused by accidental contact of his hands and arms with parts of the mechanism comprising the drilling arm and head secured thereto.
- 10 15 In the past when operating the head clamping lever, usually positioned near the top of arm 6, it has not been unusual for the radial drill operator to find it necessary to stand upon a support placed upon base 1 for grasping 75 the lever when radial drill arm bearing 7 is positioned adjacent the top of column 3.

In brief, the operation of the manually operated head clamping lever embodying our invention will greatly simplify the operation 20 of clamping the head against lateral movement on the radial drill arm since it positions the head clamping lever in a conveniently accessible location relative to the radial drill operator and dispenses with the necessity of 25 the operator standing upon the base of the radial drill or support placed thereon and reaching over parts of the radial drill mechanism for the purpose of operating the head clamping mechanism.

30 35 While we have shown and described our novel head clamping mechanism as adapted and intended for a particular type of machine it may also be used in any other situation to which it is adapted and while we have shown 40 and described a particular construction of mechanism it will be understood that it may be varied in construction and arrangement such as may be necessary for its use in combination with radial drilling machines having 45 a drilling arm and a drilling head attached thereto in varied constructions of form without departing from the scope or spirit thereof as defined in the claims.

What we claim as new and desire to secure 50 by Letters Patent is:

1. In combination with a radial drill having a head, an arm and a spindle, a horizontal upper rail and a horizontal lower rail integral with said arm, said lower rail having 55 an angular surface on the bottom thereof, a horizontal upper support integral with said head and having a plurality of spaced apart threaded vertical holes therein, a horizontal lower support integral with said head and having an angular surface on the top portion thereof adapted to engage said angular surface of said lower rail, spaced apart bosses integral with said head and positioned on the front inner corner thereof and having 60 vertical holes therein, a vertical rod rotat- 65
- ably received in said holes, a manually operated hand lever secured to the lower end of said rod near the lower edge of said arm and in close proximity to said spindle, a rockable lever fixed to the upper end of said rod 70 and having a horizontal slot in one end thereof, an outwardly extending horizontal bar having its inner end pivoted to said rockable arm in said slot, a plurality of spaced apart and horizontally extending crank arms, each 75 having a bifurcated end, said crank arms pivotally connected to said horizontal bar and each of said crank arms having a vertical hexagon hole in the other end thereof, a tightening screw having hexagon end received in each of said hexagon holes and having the lower ends threaded, a circumferential collar intermediate said hexagon end and said threaded end and adapted to engage the lower side of said crank arm, a 80 gib intermediate said upper support and said upper rail and adapted to be moved by said screws in contact therewith to closely engage the top surface of said upper rail when said lever is pulled outwardly whereby said angular surface of said lower rail is adapted to closely engage said angular surface of said lower support, substantially as and for the 85 purposes specified.
2. In combination with a radial drill having a head, an arm provided with a horizontal upper rail and a horizontal lower rail, said lower rail having an angular surface on the bottom thereof, a spindle mounted in said head, a horizontal upper support on said head and having a plurality of spaced apart threaded vertical holes therein, a horizontal lower support on said head and having an angular surface in the top portion thereof and adapted to engage said angular surface of said lower rail, spaced apart bosses on said head positioned in the front inner corner thereof and having vertical holes therein, a vertical rod rotatably received in said holes, a 90 manually operated hand lever secured to the lower end of said rod, a rockable lever fixed to the upper end of said rod, a horizontal bar pivoted to said rockable arm, a plurality of spaced apart crank arms pivotally connected to said horizontal bar, a tightening screw connected to each of said crank arms and having its lower end threaded through a part of said head, a gib intermediate said upper support and said upper rail and adapted to be moved by said screws 95 in contact therewith to closely engage the top surface of said upper rail when said lever is pulled outwardly whereby said angular surface of said lower rail is adapted to closely engage said angular surface of said lower support.
3. In a radial drill having an arm and a head slidably mounted upon said arm, the combination of a locking device whereby said head is locked in any desired adjusted posi- 100 105 110 115 120 125 130

tion against horizontal movement upon said arm and which comprises a vertical rod rotatably supported by said head, a hand lever rigidly secured to said rod, a rockable arm rigidly fixed to said rod, a bar pivoted to said rockable arm, a gib mounted between said head and said first-mentioned arm, a plurality of crank-arms pivotally connected to said bar, a tightening screw connected to each of said crank-arms and mounted in said head and in engagement with said gib whereby movement of said hand lever to rotate said rod is adapted to closely engage said head upon said arm through said gib to firmly hold said head in horizontal adjusted position upon said first-mentioned arm.

4. In combination with a radial drill having an arm and a head slidably mounted on said arm, a horizontal upper rail on said arm having a longitudinal upper surface, a horizontal lower rail on said arm having a longitudinal lower surface, a horizontal upper support on said head and having a plurality of spaced apart threaded vertical holes

therethrough, a horizontal lower support on 25 said head and having a holding surface adapted to slidably engage the longitudinal lower surface of said lower rail, a vertical rod rotatably supported by said head and having a hand lever thereon, a rockable arm 30 fixed to said rod, a horizontal bar pivoted to said rockable arm, a plurality of crank-arms pivotally connected to said bar, a tightening screw connected to each of said crank-arms and each having its lower threaded end 35 extending through one of said threaded vertical holes, and a gib intermediate said upper support on said head and said upper rail on said arm and adapted to be moved by said screws in contact therewith to closely engage 40 the longitudinal upper surface of said rail when said lever is actuated whereby said horizontal lower support is adapted to firmly bind against said horizontal lower rail and securely hold said head in any adjusted position desired.
